(57) **CLAIM**

The ornamental design for a solar panel, as shown and described.

DESCRIPTION

FIG. 1 is a front perspective view of a solar panel showing our design.

FIG. 2 is a rear perspective view of the solar panel in FIG. 1.

FIG. 3 is a front elevation view of the solar panel in FIG. 1. FIG. 4 is a rear elevation view of the solar panel in FIG. 1. FIG. 5 is a left side elevation view of the solar panel in FIG. 1.

FIG. 6 is a right side elevation view of the solar panel in FIG. 1.

FIG. 7 is a top plan view of the solar panel in FIG. 1; and, FIG. 8 is a bottom plan view of the solar panel in FIG. 1.

1 Claim, 8 Drawing Sheets
